UNITED STATES PATENT OFFICE

JOSEPH N. JOHNSON AND LORIN A. BUTTERFIELD, OF BURWELL, NEBRASKA

WELL CASING

Application filed October 15, 1930. Serial No. 488,947.

This invention relates to a well casing designed primarily for wells from which a large amount of water is pumped, such as city wells and wells for pump irrigation, but it is to be understood that a casing in accordance with this invention may be employed for any purposes for which it may be found applicable, and the invention has for its object to provide, in a manner as hereinafter set forth, a well casing formed of a plurality of superimposed, connected together, tubular, concrete units, each provided with a series of spaced, superposed, circumferentially extending rows of spaced openings of pyramidal contour gradually increasing in width and breadth from the outer to the inner face of the unit whereby provision is set up for sand or other matter that starts through the openings from the outside of the unit to quickly pass through to the inside of the latter and be pumped out.

Further objects of the invention are to provide, in a manner as hereinafter set forth, a well casing formed of a plurality of detachably connected concrete units and which is simple in its construction and arrangement, strong, durable, compact, thoroughly efficient when used, readily assembled and comparatively inexpensive to set up.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view in elevation and partly in section of a concrete well casing in accordance with this invention.

Figure 2 is a fragmentary view in vertical section of a pair of superimposed units connected together.

Figure 3 is a fragmentary view in vertical

section of a concrete well casing in accordance with this invention.

Figure 4 is a section on a line 4—4 of Figure 3.

Figure 5 is a section on a line 5—5 of Figure 3.

Figure 6 is an elevation of the form of reinforcing member employed for the body of each of the units or sections of the casing.

Figure 7 is a fragmentary view in vertical section of the lowermost one of the units.

The well casing is formed of a series of separate units bolted together. The casing is used at the very beginning of the starting of the well, and the units are successively employed, that is to say as each unit goes down to a ground level, another unit is added and bolted to the lower unit, and so on until the well is completed. The bolted together units provide a casing making a continuous pipe strong enough so that when the hole is down to the desired depth the well is completed. The casing is especially adapted to quick sand and other loose slipping formation as there is enough weight to take it down as fast as the core is taken out.

As the units of the sectional casing with the exception of the lowermost unit are of like construction, but one of the upper units will be described, as the description of one will apply to the others. The upper units are designated A and the bottom or lowermost unit B.

Each upper unit A comprises a tubular concrete body 1 of the desired length and of the desired inner and outer diameter. The body 1 in proximity to each end is formed with a set of spaced openings extending transversely therethrough and the purpose of such openings will be presently referred to. The openings in proximity to the upper and lower ends of body 1 are indicated at 2, 3 respectively. The openings 2 and 3 align with each other. The openings 2 at the top of one unit align with the openings 3 at the bottom of an adjacent unit, with this exception that the openings 3 at the bottom of the lower one of the upper units align with openings in the top of the lowermost unit B which will be presently referred to. That is to say

the openings 2 at the upper end of a unit align with the openings 3 of a superimposed unit and the openings 3 at the lower end of a superimposed unit align with the openings 2 of a lower unit.

The body portion 1 is formed with a series of superposed, equally spaced, circumferentially extending rows of spaced openings or slots of pyramidal contour. The openings or slots are indicated at 4. The openings or slots of one row align with the openings or slots of an adjacent row. The openings or slots of each row are closely arranged. The outer rows of the openings or slots of the series are spaced a substantial distance from the ends of body 1. Each of the openings or slots 4 gradually increases in width and breadth from the outer to the inner face of body 1. The outer ends of openings or slots 4 are of rectangular contour. The said rectangular outer ends are disposed lengthwise of body 1.

The openings 2, 3 are arranged in close proximity to the outer rows of said series of rows of openings or slots. That is to say the openings 2 are positioned in close proximity to one outer row of the series and the openings 3 in close proximity to the other outer row of the series. The openings 2, 3 are positioned at points which align with the non-perforated portion of body 1. Embedded in the body portion 1 is a set of spaced lengthwise extending reinforcing members 5 provided adjacent the ends thereof with loops 5', 5'' which align with the openings 2, 3 respectively. Extending through each opening 2 or 3 and the loop which aligns therewith is the shank of a headed bolt 6. The shanks of the bolts project a substantial distance from the outer face of body portion 1. Securing nuts 7 are carried by the shanks of bolts 6.

The upper units when in superimposed position are connected together by inner and outer oblong coupling straps 8 which coact with the bolts 6 and nuts 7 and mounted in mortised portions 8' formed in the inner and outer faces of the body portions 1. Each strap is formed with an opening 8'' near each end for the passage of the shank of a bolt. Each strap is common to a pair of units. The straps are flush with the outer and inner faces of the lower and upper portions of a unit. The mortised portions at the top of one unit register with the mortised portions at the bottom of an adjacent unit. When the coupling straps 8 are in position, the nuts 7 bind against the outer face of such straps and said units in connection with the heads of the bolt fixedly secure the straps in coupling position whereby the upper units of the casing are connected together in superimposed position.

The lowermost unit B of the casing includes a concrete body portion 9 constructed in the same manner as the body portion 1 of any of the upper units, with this exception

that the lower part of body portion 9 is of reduced outer diameter as at 10 to provide an annular shoulder 11 arranged a substantial distance above its bottom edge 12. The part 10 is formed with a set of openings 13. The body portion 9 is not formed at its lower end with mortises 8' as body portion 1. The body portion 9 has a set of upper openings 14 for the passage of bolts 6 to couple the straps 8 therewith. The body portion 9 has mortised portions 15 registering with mortised portions 8' formed in that unit A seated on unit B. Encompassing the part 10 and depending therefrom is an annular metallic shoe referred to generally at 16 which carries the weight of the sectional casing. The shoe 16 includes an upper perpendicular part 17 of uniform diameter mounted against the outer face of part 10, abutting against shoulder 11 and anchored to section B by holdfast devices 18 which extend through openings 13. The shoe 16 also includes a flared lower part 19 which is of greater height than part 17. The spaced rows of openings formed in body portion 9 and indicated at 4' are of the same arrangement and correspond to the rows of openings 4 in body portion 1. The body portion 9 is provided with reinforcing members 5 having the bolts 6 extend through the upper loops 5' and certain of the holdfast devices 18 extend through the lower loop 5''.

What we claim is:—

1. A well casing structure comprising a series of superimposed endwise abutting, one-piece tubular concrete units, each being provided with a series of spaced, circumferentially extending rows of openings, the outer rows of said series being spaced from the ends of the unit, each of said units between each of said outer rows and the ends thereof being provided with a circumferentially extending set of spaced openings, spaced sets of spaced pairs of opposed coupling members, the coupling members of each pair of a set of coupling members being positioned against the outer and inner peripheries of a pair of units and extending across the joint between the abutting ends of such units, bolts extending through the openings of each set, said coupling members carried by the bolts in the upper set of openings of a lower unit and in the lower set of openings of that unit mounted on the said lower unit, an apertured shoe encompassing the lower portion of the lowermost unit and extending outwardly from the latter, the bolts extending through the set of lower openings of the lowermost unit passing through the apertures in the shoe, clamping nuts carried by and coacting with said bolts for securing said members and shoe in position, and spaced reinforcing means for, embedded within and extending lengthwise of each unit and connected adjacent their ends to said bolts.

2. A well casing comprising a plurality of superimposed, endwise abutting, hollow one-piece concrete units, each having superposed circumferentially extending rows of 5 openings, spaced inner coupling members positioned against the inner peripheries and extending across the joints between the abutting ends of the units, spaced outer coupling members positioned against the outer 10 peripheries and extending across the joints between the abutting ends of the units, the inner members aligning with the outer members, a shoe encompassing the lower end of the lowermost unit and depending therefrom, headed bolts extending through the upper and lower ends of each of the aligning members and through the openings of the upper and lower ends of each pair of abutting units and through said shoe, clamping 15 nuts mounted on said bolts and lengthwise extending reinforcing members embedded in said units and anchored by said 20 bolts.

3. A well casing comprising a plurality 25 of endwise abutting tubular units, each provided with a series of superposed, spaced circumferentially extending rows of spaced openings, spaced lengthwise extending reinforcing members embedded in each unit 30 and each formed with a loop in proximity to each end thereof, spaced pairs of coupling members, the coupling members of each pair opposing each other, arranged against the inner and outer peripheries and extending 35 across the joints between the abutting ends of the units, and holdfast means including bolts extending through the outer rows of the series of rows of openings of each unit, through the upper and lower ends of each 40 pair of coupling members and through said loops for anchoring said coupling and reinforcing members to said units.

In testimony whereof, we affix our signatures hereto.

45 JOSEPH N. JOHNSON.
LORIN A. BUTTERFIELD.
